Application filed April 23, 1900. Serial No. 14,052. Term of patent 7 years.

To all whom it may concern:

Be it known that I, EDGAR L. WILLIAMS, a resident of Peoria, in the county of Peoria, State of Illinois, have invented a certain new 5 Design for a Game-Board, of which the following is a specification, reference being had to the accompanying drawings, showing the same.

In the annexed drawings, Figure 1 is a plan 10 view of a game-board embodying my new design, and Fig. 2 is a view in central cross-section.

The body A of the board, which is of rectangular outline, is bounded by a raised rim 15 a. At each of its corners and within the rim a the board is provided with a pocket B. The surface of the board is provided with a cir-

cular field C, raised above the surface of the board A. The field C has defined thereon several concentric rings c, c', and c'', and at the center of the field C is formed a depression or pocket c''. Around the pocket c'' are placed the series of posts e.

The leading feature of my design consists in a central circular playing-field arranged 20 within a square board of rectangular outline.

What I claim is—
